[57] **CLAIM**

The ornamental design for a burial casket lid, as shown and described.

DESCRIPTION

FIG. 1 is a perspective view of a burial casket lid, showing our new design;

FIG. 2 is a front elevational view thereof, the rear elevational view being a mirror image thereof;

FIG. 3 is a top plan view thereof;

FIG. 4 is a right side elevational view thereof, the left side elevational view being a mirror image thereof; and

FIG. 5 is a bottom plan view thereof;

FIG. 6 is a second embodiment of a burial casket lid;

FIG. 7 is a front view thereof, the rear elevational view being a mirror image thereof;

FIG. 8 is a top plan view thereof;

FIG. 9 is a right side elevational view thereof, the left side elevational view being a mirror image thereof; and

FIG. 10 is a bottom plan view thereof.

The broken line showing of environment in FIGS. 1, 2, 4, and 6 through 10 is for illustrative purposes only and forms no part of the claimed design.
